UNITED STATES PATENT OFFICE.

IMOGENE KIDDER AND LENNA MELTON, OF PORTLAND, OREGON.

DESIGN FOR AN ART LAMP.

Application filed August 10, 1922. Serial No. 3,338. Term of patent 3½ years.

To all whom it may concern:

Be it known that we, IMOGENE KIDDER and LENNA MELTON, citizens of the United States, residing at Portland, in the county of Multnomah and State of Oregon, have invented a new, original, and ornamental Design for an Art Lamp, of which the following is a specification, reference being had to the accompanying drawing, forming part thereof.

The figure is a front perspective view of the art lamp constituting our new design.

We claim:

The ornamental design for an art lamp, as shown.

IMOGENE KIDDER.
LENNA MELTON.
